HYDRAULIC LOG TURNER FOR SAWMILLS

Marvin E. Maynard, Chattanooga, Tenn., assignor to Corley Manufacturing Company, Chattanooga, Tenn., a corporation of Tennessee

Application July 1, 1954, Serial No. 440,591

5 Claims. (Cl. 143—99)

This invention relates to a hydraulic log turning mechanism and more particularly to a fully oscillating hydraulic log turner for co-action with a sawmill carriage.

It is an object of the invention to provide a log turning mechanism by means of which a log on the carriage is successively turned as the reciprocating carriage feeds the log longitudinally to the saw and then retracts the log for another turn on its longitudinal axis.

A further object of the invention resides in providing a log turning mechanism including a kicker bar mounted for vertical and oscillating movement and hydraulic means for raising and oscillating the kicker bar to turn and hold the log in any desired position.

A still further object of the invention resides in providing a vertical movable kicker bar having teeth for engaging the log to be turned, a hydraulic cylinder for raising the kicker bar to rotate the log and a second hydraulic cylinder for imparting lateral thrust to the kicker bar for holding the log in its adjusted position.

Another object of the invention resides in providing a mechanism of the above-mentioned character which is simple and durable in construction, reliable and efficient in operation and inexpensive to manufacture.

Other objects and advantages of the invention will be apparent during the course of the following description.

In the accompanying drawings forming a part of this specification and in which like numerals are employed to designate like parts throughout the same,

Fig. 1 is a side elevational view of the log turning mechanism,

Fig. 2 is a top plan view of the same,

Fig. 3 is a longitudinal sectional view,

Fig. 4 is a horizontal sectional view taken on line 4—4 of Fig. 3,

Fig. 5 is a vertical sectional view taken on line 5—5 of Fig. 1, and,

Fig. 6 is a vertical sectional view taken on line 6—6 of Fig. 1.

Referring to the drawings wherein for the purpose of illustration a preferred embodiment of the invention is shown the numeral 5 denotes a base member supporting at one end a vertical standard composed of channel members 6 and 7 disposed in spaced apart relation with the channels in opposed relation. Attached to the outer faces of the channel members at their upper ends are a pair of horizontal angle bars 8 and 9 that are supported intermediate their length by uprights 10 mounted on the base 5. A kicker bar composed of parallel bars 11 and 12 is mounted to reciprocate vertically in the space between the channel members 6 and 7. Mounted between the bars 11 and 12 at spaced apart intervals are a series of teeth 13 pivotally mounted on pins 14 adapted to normally project outwardly from the edges of the bars. The outer ends of the teeth are beveled, as at 15 and the teeth are supported in an inclined position by rest pins 16 carried by the bars 11 and 12. Circular bosses 17 are formed integral with the outer faces of the bars 11 and 12 at their lower ends that engage in the channels of members 6

2

and 7, slidably and pivotally connecting the kicker bar to the standard. A roller 18 is mounted between the upper ends of the bars 11 and 12 and adjacent the upper ends of said bars are lugs 19 extending laterally from the edges of the bars that support a wrist pin 20 for connecting a piston rod 21 of a hydraulic cylinder 22 to the kicker bar. The lower end of the hydraulic cylinder is pivotally mounted, as at 23, on the base 5. Upon admitting fluid under pressure to the hydraulic cylinder the kicker bar is raised upwardly and the upward movement is limited by stop blocks 24 mounted in the channel members adjacent their upper ends which are engaged by the bosses 17 on the kicker bar. A guard plate 25 bridges the channel members at their upper end so that when the kicker bar moves downwardly the teeth engage the upper edge of the guard plate and are thereby swung inwardly.

Oscillating movement of the kicker bar is controlled by a hydraulic cylinder 26 pivotally connected at one end, as at 27, to a cross member 28 at the outer ends of the horizontal angle bars 8 and 9. The piston rod 29 of the cylinder 26 is pivotally connected to a wrist pin 30 mounted in one end of a slidable frame 31 having a shaft 32, Figs. 4 and 6, at its opposite end on which is mounted a pair of rollers 33 disposed between upper and lower tracks 34 and 35 formed integral with angle bars 8 and 9. A connecting link 36 mounted on the center of shaft 32 extends between the bars 11 and 12 forming the kicker bar and has a transverse pin 37 at its end that is retained between the bars by guide bars 38 attached to the inner edges of bars 11 and 12. Roller bearings 39 mounted on shaft 32 engage the guide bars 38 to permit free sliding movement of the kicker bar. Movement of the kicker bar in a backward direction is limited by stop blocks 40 mounted on the upper tracks 34 intermediate their length. A cross member 41 between the bars 8 and 9 supports a strap anchor 42 that embraces the cylinder 26 and holds it in a horizontal position.

In operation the log turning mechanism is positioned adjacent the reciprocating carriage of a sawmill so that the teeth of the kicker bar are against the log supported by the carriage. Upon admitting fluid to the hydraulic cylinder 22, the kicker bar is raised vertically and the teeth 13 rotate the log in a counter clockwise direction.

If fluid is admitted to the horizontal cylinder 26 the kicker bar is oscillated in a forward direction forcing the log against the knee of the headblock and thus arresting the rotating movement of the log at any desired angular position. By suitable control valves the operation of the cylinders 22 and 26 may be independently or jointly controlled to provide a combination of movements to the kicker bar to turn the log and hold it in the desired position.

It is to be understood that the form of the invention herein shown and described is a preferred example of the same and changes in the shape, size and arrangement of the parts may be made without departing from the invention or scope of the claims.

Having thus described my invention, I claim:

1. A log turning mechanism comprising a vertical standard composed of spaced channel members, a kicker bar disposed between said channel members having circular bosses formed on its lower end disposed in the channels of said members for sliding and pivotal movement, spaced horizontal bars connected to and extending from the upper end of said standard, a hydraulic cylinder mounted between said horizontal bars having its piston slidably connected to said kicker bar, and a substantially vertical hydraulic cylinder pivotally mounted at its lower end having its piston connected to said kicker bar adjacent its upper end.
2. In a hydraulic log turner for sawmills, a vertical standard composed of spaced parallel bars, a kicker bar

disposed intermediate the bars of said standard, means pivotally and slidably mounting said kicker bar in said standard, teeth pivotally mounted in the front face of said kicker bar normally projecting therefrom, means at the upper end of said standard for engagement with said teeth to swing the teeth inwardly when said kicker bar moves downwardly, a horizontal frame connected to and extending horizontally from the upper end of said standard, a slidable frame movable longitudinally of said horizontal frame, a connecting link between said slidable frame and said kicker bar having sliding connection with the kicker bar, a hydraulic cylinder on said horizontal frame for moving said slidable frame, a second hydraulic cylinder pivotally mounted on one end in substantially parallel relation to said standard, the piston rod of said cylinder having pivotal connection with the upper end of said kicker bar.

3. In a hydraulic log turner for sawmills, a vertical standard composed of spaced channel members, a kicker bar disposed intermediate said channel members, circular bosses formed on the sides of said kicker bar adjacent its lower end for engagement with the channels of said members to slidably and pivotally support said kicker bar in said standard, a series of teeth pivotally mounted in the front face of said kicker bar, means across the front face of said standard at its upper end for engaging said teeth to swing them inwardly upon downward movement of said kicker bar, spaced horizontal bars connected to and extending horizontally from the upper end of said standard, a horizontal hydraulic cylinder disposed intermediate said horizontal bars, a reciprocating frame supported by said horizontal bars having one end connected to the piston rod of said horizontal cylinder, means at the opposite end of said frame having sliding connection with said kicker bar, roller bearings carried by said frame in bearing engagement with the inner face of said kicker bar, a vertical hydraulic cylinder disposed substantially parallel to said standard pivotally mounted at its lower end and having its piston rod extending upwardly between said horizontal bars and pivotally connected to the upper end of said kicker bar.

4. In a hydraulic log turner for sawmills, a vertical standard composed of spaced channel members, a kicker bar disposed intermediate said channel members having circular bosses formed on its sides adjacent the lower end, said bosses having engagement with the channels of said members to pivotally and slidably support said kicker bar in said standard, a series of teeth pivotally mounted in the front face of said kicker bar adapted to project beyond the front face, a guard plate secured to the front face of said standard at its upper end for engagement with said teeth to swing the teeth inwardly upon downward movement of said kicker bar, spaced horizontal bars connected to and extending horizontally from the upper end of said standard, a hydraulic cylinder

mounted longitudinally between said horizontal bars, a reciprocating frame supported by said horizontal bars having one end connected to the piston rod of said hydraulic cylinder, a connecting link between said frame and said kicker bar, a second hydraulic cylinder pivotally mounted at its lower end adjacent said standard in substantially parallel relation to the standard, said cylinder having its piston rod extending between said horizontal bars and pivotally connected to the upper end of said kicker bar.

5. In a hydraulic log turner for sawmills, a vertical standard composed of spaced channel members disposed in parallel relation with the channels in confronting relation, a kicker bar composed of spaced parallel bars disposed between the channel members of said standard, flanges extending inwardly from the rear edges of the bars of said kicker bar to form a longitudinal slot in the rear face thereof, circular bosses formed integral with the outer faces of the bars of said kicker bar as their lower ends for engagement in the channels of the channel bars of said standard to pivotally and slidably mount said kicker bar in said standard, a series of teeth pivotally mounted between the bars of said kicker bar normally projecting beyond the front face thereof, a guard plate secured to the front face of said standard at its upper end for engagement with said teeth to swing the teeth inwardly upon downward movement of said kicker bar, spaced horizontal bars connected to and extending horizontally from the upper end of said standard, a hydraulic cylinder mounted longitudinally between said horizontal bars, a reciprocating frame supported by said horizontal bars having one end connected to the piston rod of said hydraulic cylinder, a connecting link connected to the other end of said frame adapted to extend through the slot in the rear face of said kicker bar, a transverse pin extending through the free end of said link and overlapping the inner faces of the flanges of said kicker bar, roller bearings carried by said frame in bearing engagement with the outer faces of the flanges of said kicker bar, a second hydraulic cylinder pivotally mounted at its lower end adjacent said standard in substantially parallel relation thereto, said cylinder having its piston rod extending upwardly between said horizontal bars and pivotally connected to the upper end of said kicker bar.
